(57) CLAIM

The ornamental design for a bucket for dehumidifier, as shown and described.

DESCRIPTION

FIG. 1 is a perspective view of a bucket for dehumidifier, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is an exploded perspective view of a dehumidifier showing the bucket in an environment of use.

The broken line showing of a bucket for a dehumidifier is included for the purpose of illustrating portions of the article and forms no part of the claimed design; the broken line showing of a dehumidifier is included for the purpose of illustrating environmental structure and forms no part of the claimed design.
